CLAIM

The ornamental design of the claw hammer head, as shown and described.

DESCRIPTION

FIG. 1 is a side elevation view of a claw hammer head illustrating the new design.

FIG. 2 is a side elevation view of the claw hammer head of FIG. 1 showing the side of the claw hammer head opposite the side shown in FIG. 1.

FIG. 3 is an elevation view of the claw hammer head of FIGS. 1 and 2 viewed toward the striking surface, from the left of FIG. 1.

FIG. 4 is an elevation view of the claw hammer head viewed toward the claw apparatus, from the right of FIG. 1; and, FIG. 5 is a top view of the claw hammer head viewed from above relative to FIG. 1.
